UNITED STATES PATENT OFFICE

WALTER F. KEENAN, JR., OF PELHAM, NEW YORK, ASSIGNOR TO FOSTER WHEELER CORPORATION, OF NEW YORK, N. Y., A CORPORATION OF NEW YORK

SUPERHEATER

Application filed May 19, 1926. Serial No. 110,100.

The general object of the present invention is to provide improvements in construction and arrangement of a superheater of the type employed in water tube boilers comprising rising looped or U-tube elements swept over by the heating gases after the latter have first passed over a portion of the boiler heating surface and are correspondingly cooled below the combustion chamber temperature. More specifically, the object of the invention is to provide an arrangement of U-tube superheater elements adapted to the restricted spacial conditions of water tube boilers, and characterized by the arrangement of the superheater elements in banks separated by a space into which elements from either bank can be readily removed without interference with other elements, in effecting replacement of elements, and in which space soot blower elements may be so disposed as to secure a satisfactory coverage of the superheater elements by the cleaning jets discharged by the soot blowing elements which are accessible for inspection and repairs. The arrangement of the superheater elements in spaced apart banks permits of improvements in the superheater supporting provisions, and in particular permits the lower superheater elements located in a relatively high temperature zone to be readily carried by water cooled supports, i. e. the boiler water tubes, while the upper superheated elements located in a cooler zone may be carried on ordinary steel and cast iron supports. The separation of the superheater elements into separately supported banks reduces the weight which must be impressed upon any one set of supports.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

Of the drawings:
Fig. 1 is a vertical section;

Fig. 2 is a partial section on the line 2—2 of Fig. 1;

Fig. 3 is a view taken similarly to Fig. 1, illustrating a modified construction; and

Fig. 4 is a partial section taken similarly to Fig. 1 but on a larger scale.

In Figs. 1 and 2 I have illustrated the use of my invention in a superheater boiler A of the so-called drop-bank, cross drum, horizontal water tube type, with the superheater B located between the upper and lower banks of water tubes A' with its heat absorbing surface at the high temperature side of the transverse baffle C. The latter extends across the upper bank of water tubes and the space between the two banks from the upper end of the longitudinal baffle C' which rests on top of the lower bank of water tubes and extends from the lower ends of the latter for a distance of something like half the length of the water tubes.

The superheater B, as shown in Figs. 1 and 2, comprises an upper inlet header B' and a lower outlet header B². The headers B' and B² are horizontal and transverse to the water tubes, and are located adjacent the top and the bottom respectively, of the space between the two banks of water tubes, and adjacent to, and at the low temperature side of the baffle C. The superheater U-tube elements have their legs generally parallel to the water tubes A', and are arranged to form two spaced apart banks located one adjacent the top, and the other adjacent the bottom of the inter-deck space of the boiler. As shown, the lower bank is formed by a single row of U-tube elements B³, while the upper bank of superheater elements comprises two sets of elements B⁴ and B⁵; the elements B⁴ having their legs spread far enough apart to straddle the row of elements B³. The various elements B³, B⁴, and B⁵ may be all alike in form, and advantageously though not necessarily, each is of the well known Foster element type, comprising an inner steel tube and externally corrugated tubular casing sections of cast iron.

The lower end of the lower legs of each element B³ is connected into the superheater header B², while the lower end of the upper

leg of the element is connected to the lower end of a corresponding vertical header B^6 . The lower end of one element B^4 and of one element B^5 are connected to the upper end of each header B^6 . With this arrangement the steam flow through each header B^6 passes in a single stream through the corresponding element B^3 and in divided streams through the corresponding elements B^4 and B^5 . This gives a higher stream velocity in the portion of the superheater where the steam and gas temperatures are relatively high than in the portion of the superheater where the steam and gas temperatures are lower which is somewhat desirable though the attainment of general advantages of my invention does not depend on the number of sets of elements in either bank.

As shown, the elements B^3 are supported adjacent their free ends and at points intermediate their ends by supporting provisions including channel bars D and D' , and spacers d' extending transversely to the elements. The bars D and D' rest on and are carried by the top row water tubes of the lower tube bank. The elements B^4 and B^5 are supported adjacent their free ends, and intermediate their ends by supporting provisions including beams D^2 and D^3 respectively, and spacers d' . The beams D^2 and D^3 are suspended from the roof of the boiler housing by means of suitable hanger elements E and E' which extend through the upper bank of water tubes A' , and are cooled by contact with the latter in the manner disclosed in my prior Patent No. 1,416,835.

With the space between the upper and lower banks shown and described, superheater elements from either bank may readily be moved into and through said space in removing old, and installing new elements. Advantageously said space is wide enough to receive a workman, who may enter the space through normally closed manhole openings A^2 in the side walls of the boiler, and thereby facilitates inspection and repair operations.

The separation of the superheater elements into upper and lower banks as described, provides a space in which soot blower tubes F may be disposed as shown, so that the jets of cleaning fluid discharged by them will effectively clean practically all portions of the superheater elements. This arrangement also permits ready access to the bearings F' for the soot blower tubes F when the latter are of the well known rotatable tube type shown. The soot blower tubes F advantageously extend transversely to water tubes, with the intermediate bearings F' for the soot blower tubes F attached to adjacent superheater elements in the usual manner. The arrangement of the soot blower tubes F above rather than below the lower bank of superheater elements as shown, is advantageous because of the resultant decrease in

the temperatures to which the soot blower tubes are subjected.

The reduction of the weight of the portion of the superheater which must be supported by any one set of supporting provisions, and in particular which must be supported by any one set or row of boiler water tubes is of practical importance and permits of the use of an extent of superheating surface and length of superheater path of steam flow greater than would otherwise be practically feasible in some superheater boiler installations.

The invention is not limited to use in a drop bank boiler with the superheater located in the inter-deck space, but may be employed when the superheater is located in the more usual position above the water tubes as shown in Fig. 3. The superheater shown in Fig. 3 is practically identical in form with that shown in Figs. 1 and 2, but in Fig. 3 the superheater is located in the space above the inclined water tubes and the superheater elements have portions of their lengths at each side of the transverse baffle C and the extension C^2 thereof. In Fig. 3 the superheater headers are shown as located at the low temperature side of the baffle C^2 which forms one side wall of the final heating gas pass of the boiler. The lower superheater elements B^3 are shown in Fig. 3 as supported by the water tubes A^3 beneath them as are the elements B^3 in Figs. 1 and 2. The elements B^4 and B^5 of Fig. 3 are supported by beams D^2 and D^3 and hangers E and E' as shown in Fig. 1, and by an additional supporting beam D^4 and set of hangers E^4 . In the type of boiler shown in Fig. 3, manholes A^2 are advantageously provided at the free end of, and above the upper bank of superheater elements, as well as between the two banks of superheater elements, and soot blower tubes F may well be provided above the upper bank of superheater elements as well as between the two banks of elements.

While in accordance with the provisions of the statutes, I have illustrated the best forms of my invention now known to me, it will be apparent to those skilled in the art that changes may be made in the form of the apparatus disclosed without departing from the spirit of my invention, as set forth in the appended claims, and that certain features of my invention may sometimes be used to advantage without a corresponding use of other features.

Having now described my invention, what I claim as new and desire to secure by Letters Patent is:

1. In a superheater boiler, a superheater comprising two banks of superheater elements separated by a space sufficient to permit the entrance of a workman between said banks for inspection and repair purposes and adapted to receive elements from either bank with-

out interference with elements in the other bank, and soot blower tubes transversely mounted in said space and supported from one of said banks and adapted to discharge 5 cleaning fluid jets against said elements.

2. In a boiler, the combination with a bank of water tubes, of a superheater located above said water tubes and comprising a bank of superheater elements supported by said water tubes and a second bank of superheater elements above and spaced away from the first mentioned bank of superheater elements, and means independent of said water tubes for supporting said second bank of super- 10 heater elements.

3. A superheater comprising a bank of looped tube superheater elements, a second bank of looped tube superheater elements generally parallel to the first mentioned bank 20 of elements and laterally displaced therefrom, vertically elongated headers transverse to said elements connecting the adjacent legs of the elements in the two banks, inlet and outlet headers to which the other legs of the 25 elements in the two banks are connected and means independently supporting each of said banks.

4. The combination with a horizontal water tube boiler having upper and lower banks 30 of water tubes, of a superheater located in the space between the banks of water tubes and comprising a lower bank of superheater elements supported by the water tubes in the lower bank, and an upper bank of super- 35 heater tube elements spaced away from the lower bank of elements and supported independently of the lower bank of water tubes.

5. The combination with a horizontal water tube boiler having upper and lower banks 40 of water tubes, of a superheater located in the space between the banks of water tubes and comprising a lower bank of superheater elements supported by the water tubes in the lower bank, and an upper bank of super- 45 heater tube elements spaced away from the lower bank of elements and supporting provisions for the upper bank of superheater elements extending into contact with and cooled by the upper bank of water tubes.

50 6. The combination with a horizontal water tube boiler having spaced apart upper and lower water tubes, of a superheater located in the space between said upper and lower water tubes and comprising a lower 55 and an upper bank of superheater elements and soot blower tubes extending between said banks, the latter being spaced apart sufficiently to permit the entrance of a work- man between said bank for soot blower in- 60 spection and repair purposes.

7. A superheater comprising a bank of U- tube superheater elements, a second bank of U-tube superheater elements generally parallel to the first mentioned row of elements and laterally displaced therefrom, elongated 65

headers transverse to the elements each connecting one leg of a corresponding element in the first mentioned bank to adjacent legs of two elements in the second mentioned bank, and inlet and outlet headers to which the 70 other legs of the elements in the two banks are connected.

Signed at New York city, in the county of New York, and State of New York, this 18th day of May, A. D. 1926. 75
